UNITED STATES PATENT OFFICE

104,943

DESIGN FOR A SPOON OR SIMILAR ARTICLE

Frederick W. Koonz, Bernardston, Mass., assignor
to Rogers, Lunt & Bowlen Company, Green-
field, Mass., a corporation of Massachusetts

Application February 27, 1937, Serial No. 67,898

Term of patent 14 years

To all whom it may concern:

Be it known that I, Frederick W. Koonz, a citizen of the United States of America, residing at Bernardston, in the county of Franklin and State of Massachusetts, have invented a new, original, and ornamental Design for a Spoon or Similar Article, of which the following is a specification, reference being had to the accompanying drawing, forming part thereof.

In said drawing:

Fig. 1 is a plan view of a spoon showing my new design;

Fig. 2 is a fragmentary view showing the rear of the upper end of the spoon handle;

Fig. 3 is an edge view corresponding to Fig. 2;
and

Fig. 4 is a section taken on line 4—4 of Fig. 1.

The dominant feature of the design resides in the ornamental appearance produced by the chased decorative panel, extending down the front of the spoon handle, as shown particularly in Fig. 1.

I claim:

The ornamental design for a spoon or similar article, substantially as shown and described.

FREDERICK W. KOONZ.
